UNITED STATES PATENT OFFICE.

HAROLD E. YARROW, OF GLASGOW, SCOTLAND.

PREHEATING OF AIR SUPPLIED TO THE FURNACES OF WATER-TUBE BOILERS.

Application filed April 6, 1920. Serial No. 371,749.

To all whom it may concern:

Be it known that I, HAROLD EDGAR YARROW, a subject of the King of Great Britain, residing in Glasgow, Scotland, have invented certain new and useful Improvements Relating to the Preheating of Air Supplied to the Furnaces of Water-Tube Boilers, of which the following is a specification.

10 The invention relates to means for preheating the air supplied to the furnaces of water tube boilers by means of the furnace gases, and consists in an improved disposition of the heating device and of the arrangements by which the air is led to and from the heater.

According to the invention the heaters are placed in the upper part of the boiler casing closely adjacent to the uptake and 20 preferably two sets of heaters are provided symmetrically placed on either side of a central longitudinal plane of the boiler. The tubes are arranged horizontally and preferably at right angles to the axis of the steam and water drum. Cold air is drawn in by 25 fans to the heaters through pockets preferably extending across the central part of the left and right side of the boilers; it then passes to compartments provided at the ends

30 of the boiler and is led thence by passages above the heaters to the inner ends of the latter and after flowing past horizontal tubes disposed at right angles to the steam drum and heated by the furnace gases, is led into 35 a pocket extending across the boiler and thence to vertical partitioned spaces at the ends of the boiler and finally to trunks leading to the furnaces.

Also, preferably other portions of cold 40 air are drawn through compartments at the sides of the boiler and are led between inner and outer casings of the boiler to the passages above the heaters.

In the accompanying drawing which represents an example of the arrangement of air heaters according to the invention, Fig. 1 is a side elevation of a water tube boiler and Figs. 2 and 3 are, respectively, sections on the lines 2-2 and 3-3 of Fig. 1 looking 45 in the direction of the arrows.

A is the steam and water drum, B', B² superheaters placed respectively between two sets of water drums C', C² and D', D². The furnace gases, after traversing the

water and superheater tubes and dampers 55 E', E² enter the tubes f' f² of the air heaters F', F², whence they pass to the uptake G.

Cold air is drawn into pockets H¹ and H² at the sides of the boiler by mechanically driven fans h or by an induced draft fan 60 in the main funnel and is led thence into vertical compartments I', I², I³ and I⁴ at the ends of the boiler; these compartments are enclosed by vertical division plates K', K², K³ and K⁴ provided at each end of the 65 boiler. Division plates L', L², L³, and L⁴ inclined towards the centre of the boiler and extending to the inner ends of the heaters F', F² cause the cold air to pass into passages J', J² above the heaters and to enter 70 the heaters at the inner ends, whence after traversing past baffles M', M², it emerges into triangular shaped pockets N', N². From these pockets the heated air passes to partitioned compartments O', O² between 75 the compartments I', I², I³ and I⁴ and thence is led by suitable trunks to the furnaces indicated by the bars R.

Also, air flowing between the inner and outer casings of the boiler at Q', Q² is led 80 into the passages J', J² and enters the heaters with the air the course of which is described above.

The path of the cold air is shown by plain and of the heated air by feathered arrows. 85

The arrangement of the air heater is obviously not limited to the case shown in which the superheaters are placed between two water drums; the arrangement according to the invention can be conveniently 90 used where the superheaters are differently placed or in other dispositions adapted for water tube boilers.

Having thus described the nature of the said invention and the best means I know 95 of carrying the same into practical effect, I claim:—

1. A water tube boiler, water and also steam and water drums and furnace therein, pockets extending parallel to said drums 100 along the sides of the boiler, means for inducing a flow of air into said pockets, compartments at the ends of the boiler into which the air from said pockets flows, an uptake and boxes closely adjacent thereto, 105 tubes in said boxes heated by the products of combustion, past which tubes the air from said compartments flows, pockets ex-

- tending parallel to said drum along the sides of the boiler into which pockets the heated air passes from said boxes, compartments arranged by the side of the first mentioned compartments separated therefrom by vertical division plates and receiving the heated air from said last mentioned pockets, and passages leading from said last mentioned compartments to the furnaces.
- 10 2. A water tube boiler, water and also steam and water drums and furnace therein, pockets extending parallel to said drums along the sides of the boiler, means for inducing a flow of air into said pockets, compartments at the ends of the boiler into which the air from said pockets flows, an uptake and boxes closely adjacent thereto, tubes in said boxes heated by the products of combustion, past which tubes the air from said compartments flows, division plates in said boxes inclined towards the center of the
- 15
- 20

boiler and extending to the inner ends of said boxes.

3. A water tube boiler, water and also steam and water drums and furnace therein, pockets extending parallel to said drums along the sides of the boiler, means for inducing a flow of air into said pockets, compartments at the ends of the boiler into which the air from said pockets flows, an uptake and boxes closely adjacent thereto, tubes in said boxes heated by the products of combustion, past which tubes the air from said compartments flows, an inner and outer casing at the upper part of the boiler, between which casings cold air is drawn in and led to the heating boxes where it is heated and mixes with the air drawn in from said pockets.

In testimony whereof I have signed my name to this specification.

HAROLD E. YARROW.
